TUBE MILL AND METHOD OF OPERATING
SAME, INCLUDING DISCHARGINGFrank J. Gavin, Baltimore, Md., assignor to Crown
Cork & Seal Company, Inc., Baltimore, Md., a
corporation of New York

Application August 4, 1943, Serial No. 497,370

5 Claims. (Cl. 241—30)

1

The present invention relates to improvements in method and apparatus for reducing materials in mills of the ball type and for effecting the discharge of the reduced material from such mills. As for the reducing operation, it is an object of the invention to enhance the effectiveness of the disintegrating action by causing the disintegrating media to move in a path or circuit which increases their impact, as opposed to attritive, action. As for the discharge operation, it is an object of the invention to enable the reduced material to be discharged alone by maintaining the charge of disintegrating media stable in the mill. How these objects may be accomplished will be described with reference to the accompanying drawings wherein:

Figure 1 is a side elevation of a mill in accordance with the invention;

Figure 2 is a section on line 2—2 of Figure 1;

Figure 3 is a section on line 3—3 of Figure 1;

Figure 4 is a section on line 4—4 of Figure 1 with certain elements removed;

Figure 5 is an elevation of a detail; and

Figure 6 is a transverse section of the detail appearing in Figure 5.

In my application Serial No. 346,452, now Patent No. 2,334,258, granted November 16, 1943, of which the present application is a continuation-in-part, the herein-disclosed mill was disclosed as an adjunct to a process of making finely divided metal, particularly aluminum powder, useful in the coating arts. It will be understood, however, that the improvements which constitute the present invention are useful in mills of the ball type regardless of the nature of the material to be reduced.

Referring to Figures 1, 2 and 3 of the drawings, reference numeral 10 designates generally a drum which comprises a cylindrical shell 11 which is bolted to axially extending lifters 12 through a cylindrical liner 13. The ends of the drum are closed by circular plates as at 14, Figures 2 and 3, and secured to these end members centrally thereof are hollow trunnions which are journaled in bearings at the upper ends of pedestals 15 and 16 on an axis which is horizontal, or generally so. Midway between its ends the drum is provided with a charging opening closed by a removable cover 17 and opposite the charging opening is a discharge opening which is closed by a removable cover 18 (Fig. 3). The drum is rotatable through a ring gear 19 fixed to one end of the drum.

Journaled in the hollow trunnions of the drum on the axis of the latter is a shaft 20 and sup-

2

ported by this shaft within the drum in generally radial relation and in the same plane are a number of arms 21 which are longitudinally slotted to receive bolts 22 which secure a plate or apron 23 against one side of the arms with the capability of radial adjustment. The plate 23 extends from end to end of the drum with slight end clearances and projects radially into adjacency with the circle described by the inner extremities of the lifters 12. The width of the plate 23 is such that a space 24 exists between its inner edge and the shaft 20. The shaft 20 projects outwardly of the left-hand trunnion, Figure 1, and has fixed thereto a worm wheel 25 which is engaged by a worm 26 whereby shaft 20 may be rotated to adjust plate 23 to various positions for the purposes which will be hereinafter explained; the worm automatically locking the shaft in adjusted position. The drum contains a charge 27 of disintegrating media, here shown as steel balls, the proportion of material to be reduced to the balls being generally maintained, for example, at about 1 to 15 to 1 to 20 by weight.

When the mill is to be placed in operation 25 the shelf 23 is preferably adjusted to the upwardly extending position shown in dot and dash lines in Figure 2 until the mill has attained its operating speed and this speed is less than critical, i. e., insufficient to cause the balls to be carried around by centrifugal force in the pockets between the lifters. This means that the balls will be carried upwardly a distance on the ascending inner wall of the drum and then will tend to tumble or cascade downwardly with 30 a largely attritive effect on the material to be reduced. However, in accordance with the invention, after the operating speed of the drum has been attained the plate 23 is adjusted, by clockwise rotation of the shaft 20, to a position 35 like that shown in Figure 2 wherein it extends toward the ascending wall of the drum so as to be able to catch the media tumbling from the top of the ascending layer and direct them toward the center of the drum to drop through the opening 24 on to the material to be reduced 40 so that a predominantly impact action is afforded. In other words, at least a large portion of the charge is caused to follow a loop-like path between the ascending and descending sides of the drum in contact with the former and clear of the latter. Preferably, the clearance between the outer edge of apron 23 and the circle of the inner extremities of the lifters is less than the diameter of the minimum ball size so that all 45 balls which are lifted above the apron will have 50

to fall onto the latter and so move to the opening 24.

The described arrangement, by which the balls are caused to fall free on substantially a full radius of the drum, greatly increases their disintegrating effect with a consequent saving in the time required to effect reduction.

When the reducing operation has been completed, shaft 20 is rotated to bring plate 23 into a downwardly extending position and continued rotation of the drum causes the ball charge to be localized between the plate and the ascending side of the drum. After this has occurred, rotation of the drum is arrested with the discharge opening at the bottom and at the opposite side of plate 23 from the ball charge. Bolts 22 are loosened and plate 23 is lowered close to the liner so as to serve as a complete barrier for the charge, as shown in Figure 3. If the drum is stopped with the lifter which is directly at the right hand side of the discharge opening, Figure 3, in register with the barrier 23, the balls will be completely maintained away from the discharge opening without downward adjustment of the barrier being necessary. Where, as described in the parent application, the material is finely reduced in the presence of considerable liquid, the slurry can now be drained off while the balls are maintained in stable condition against escape through the discharge opening. The lifters should be notched immediately adjacent the liner 13, or their ends should be spaced somewhat from the end walls, or both, so that the pockets will drain as completely as possible, but in any case the drain openings should not be of sufficient size to pass the minimum units of the charge.

In order to further stabilize the ball charge at one side of the discharge opening, permanent magnets in the form of bars 28 may be inserted in the heap as indicated in Figure 3, these bars being insertable through the charging opening, which is at or adjacent the top of the drum, or they may be inserted also through the hollow trunnions where these are large enough, or through doors provided in the end walls. The magnets serve to lock the mass of balls together so that the mass is completely stabilized.

In Figure 4, the charge is shown as being stabilized by the magnets 28 alone, the magnets being successively placed in position and the balls heaped thereon. Obviously, the magnet system can be used only when the material to be reduced is not subject to magnetic attraction and the disintegrating media are. In such case, the magnets serve the additional function of taking with them, when removed from the media, any foreign matter which is magnetically attractive.

Instead of the simple bar magnets shown in Figures 3 and 4, I may utilize a magnet arrangement such as is shown in Figures 5 and 6 wherein reference numeral 29 designates a non-magnetic bar which carries, through clamps 30, a number of aligned permanent magnets 31 in the form of short rod lengths.

It will be understood that the showing herein is for the purpose of illustration and is not intended to be restrictive of the invention which extends to all variations in apparatus and procedure coming under the terms of the following claims.

I claim:

1. The combination with a mill having a drum rotatable on a horizontal axis and provided with a peripheral discharge opening, of a longitudinally extending plate in the drum, and a shaft

extending coaxially into said drum and supporting said plate for adjustment edgewise into fixed positions toward and away from the inner periphery of the drum, means for rocking said shaft to bring said plate to a position wherein it projects toward the bottom of the drum to serve as a barrier for holding a charge of disintegrating media away from said discharge opening when the latter is in discharging position at the bottom of the drum.

2. The method of discharging reduced non-magnetic material in slurry form from a mill of the type comprising a drum rotatable on a horizontal axis, said drum containing a charge of magnetically attractive disintegrating media and having a peripheral discharge opening and a cover therefor, said method comprising rotating the drum to position said opening at the bottom of the drum, holding the drum stationary, exerting lateral force on the charge to hold the charge at one side of said opening and simultaneously applying magnetic force to the charge to lock the charge together, and removing the cover and allowing the slurry to drain through said opening.

3. The method of discharging reduced non-magnetic material in slurry form from a mill of the type comprising a drum rotatable on a horizontal axis, said drum containing a charge of magnetically attractive disintegrating media and having a peripheral discharge opening and a cover therefor, said method comprising rotating the drum to position said opening at the bottom of the drum, holding the drum stationary, heaping the charge on a bottom portion of the drum at one side of the opening and applying magnetic force to the heaped charge to maintain it in position at said one side of the opening, and removing the cover and allowing the slurry to drain through said opening.

4. The method of discharging reduced non-magnetic material in slurry form from a mill of the type comprising a drum rotatable on a horizontal axis, said drum containing a charge of magnetically attractive disintegrating media and having a peripheral discharge opening and a cover therefor, which comprises rotating the drum to position said opening at the bottom of the drum, holding the drum stationary, heaping the charge on a bottom portion of the drum at one side of the opening, and embedding magnetic means in the heaped charge to maintain it in position at said one side of the opening, and removing the cover and allowing the slurry to drain through said opening.

5. A mill comprising a drum mounted for rotation on a horizontal axis and provided with a peripheral discharge opening, a shaft extending into the drum coaxially therewith, and an apron in the drum extending lengthwise of said shaft and supported thereby in generally radially extending relation, and means for fixing said apron in a position wherein it projects into adjacency with a layer of grinding media in the drum which is carried upwardly a distance on the ascending inner side of the drum when the drum is rotated at less than critical speed so that the apron receives the media as they tumble and directs them toward the drum center to drop from adjacent said shaft onto the material to be reduced, said means being adjustable for fixing said apron in a downwardly projecting position so that it can serve to retain the grinding media at one side thereof when said discharge opening is at the bot-

tom of the drum and at the other side of said apron.
